ABSTRACT: An isolating ring for isolating a lamp from a circular rimmed housing. The isolating ring consists essentially of a resilient annular which has an internal gallery for receiving the rim of the housing. The housing rim has cutaway portions at intervals and the annulus of the isolating ring has integral lugs which extend inwardly through the cutaway portions and which bear against the lamp. Because the lugs register with the cutaway portions, and because one of the lugs is shaped to register with a protruding portion of the lamp, relative shifting between the isolating ring, the lamp and the housing is prevented. The isolating ring has an inward lip which urges the lamp against the lugs.

PATENTED AUG 24 1971

ISOLATING RING FOR LAMP ASSEMBLY

This invention relates to isolating rings for use with lamp assemblies where it is necessary to mount the lamp itself, usually a sealed-beam type, in shock-free relationship with the lamp housing.

The isolating ring to which this invention is directed is particularly adapted for use with rugged motor vehicles, such as trucks, which are often driven over very rough terrain and must of necessity be provided with shock-free resilient mountings for vehicle headlamps and for vehicle auxiliary lamps in order to isolate the lamps from excessive vibrations which could cause lamp failure due to injury to the lighting filaments.

An isolating ring which is exemplary of the prior art over which this invention is an improvement is described in U.S. Pat. No. 3,025,390, Woodcock, issued Mar. 13, 1962 and entitled "Lamp Mounting Structure". The Woodcock patent describes a resilient ring which has one part which annularly encloses the rim of a sealed-beam lamp, and a further cylindrical part, joined integrally with the first part through an annular web. The further part is adapted snugly to embrace a cylindrical housing, and has three leg portions adapted for insertion into three openings or slots in the cylindrical housing.

One of the disadvantages of the prior art isolating rings, as exemplified in the Woodcock patent, is the difficulty of assembly, due to the necessity of inserting the legs into the holes in the cylindrical housing.

Another disadvantage of the prior art isolating ring as exemplified in the Woodcock patent is that the sealed-beam lamp has only very restricted mobility with respect to the lamp housing, because the rim of the sealed-beam lamp is fully enclosed at all points around its periphery by a full annular channel portion of the isolating ring. Because of this, the ability of the isolating ring to cushion the sealed-beam lamp from shocks in the lamp housing is diminished.

In view of the above disadvantages, it is an object of this invention to provide an isolating ring for a lamp assembly which grips a lamp rim at spaced intervals only, and which is such as to make assembly of the lamp easier and quicker.

Specifically, this invention provides, for use with a lamp housing having a circular rim, the rim defining the mouth of a cavity adapted to receive a lamp, the rim having four recesses spaced at 90° intervals, an isolating ring, said isolating ring comprising a resilient annulus, an internal gallery in said annulus for receiving said circular rim, at least three lugs protruding inwardly from said annulus and adapted to register with said recesses when said circular rim is received within said gallery, a lip extending inwardly from said annulus for engagement with a lamp and for urging the lamp toward said cavity and against said lugs, thereby completely to isolate said lamp from direct contact with said lamp housing.

One embodiment of this invention is shown in the accompanying drawings, in which like Figures denote like parts throughout the several views, and in which:

FIG. 1 is an exploded perspective view of a lamp housing and an isolating ring in accordance with this invention;

FIG. 2 is an axial view of the isolating ring of this invention, as seen from beneath in FIG. 1;

FIG. 3 is a sectional view taken along the angled section line 3-3 in FIG. 2; and

FIG. 4 is a sectional view similar to FIG. 3, showing a sealed-beam lamp, a lamp housing, and the isolating ring of this invention.

In FIG. 1, a generally hemispherical lamp housing 10 has a rim 12 defining the mouth of a cavity 13 which is adapted to receive a lamp 14 (shown in FIG. 4). The rim 12 includes an annular flange portion 16 extending substantially radially outwardly from the housing 10, and a substantially cylindrical portion 18 extending from the periphery of the annular flange portion 16 in the direction away from the cavity 13. There are four breaks or hiati 20, 21, 22 and 23 in the portion 18, and these constitute four recesses in the rim 12. Hereinafter, the

hiati 20-23 will be referred to as recesses 20-23. The four recesses 20-23 are spaced at 90° intervals around the circular rim 12.

Also seen in FIG. 1 is an isolating ring 25 which comprises a resilient annulus 28, the latter having a substantially constant cross section which is shown at the right in FIG. 3, to which attention is now directed. As is visible in FIG. 3, the cross section of the resilient annulus 28 consists of an elongated body portion 30 of which the longer dimension is substantially parallel with the axis 32 of the resilient annulus 25. The face of the elongated body portion 30 which is adjacent the axis 32 has a stepped indentation 34 of which the deeper part 36 provides an internal gallery in the resilient annulus 28 for receiving the substantially cylindrical portion 18 of the circular rim 12 of the housing 10. The shallower part 38 of the indentation 34 defines the inner wall 40 of a lip 42 which extends inwardly from the resilient annulus 25 as shown.

Turning now to FIG. 4, the sealed-beam lamp 14 is seen to include generally a lens 44, a rim 45, and a reflector portion 46. As is clearly seen in FIG. 4, the shallower part 38 of the indentation 34, in conjunction with the lip 42, is adapted to engage the outer or forward corner of the rim 45 of the sealed-beam lamp 14, while the substantially cylindrical portion 18 of the rim 12 of the lamp housing 10 is adapted to be snugly received within the gallery defined by the deeper part 36 of the indentation 34. When the lamp assembly has been put together in the manner shown in FIG. 4, the resilient annulus 25 is securely fixed about the rim 12 of the lamp housing 10, and the sealed-beam lamp 14 is in engagement with the combination of the lip 42 and the shallower part 38 of the indentation 34.

The isolating ring 25 is provided with four lugs 48 protruding inwardly from the resilient annulus 28, and being adapted to register with the recesses 20, 21, 22 and 23 of the rim 12 when the rim is received within the gallery formed by the deeper part 36 of the indentation 34. The lugs 48 are spaced at 90° intervals around the resilient annulus 28. As is particularly visible in FIGS. 3 and 4, each lug 48 is integral with the resilient annulus 28 at the base of the deeper part 36 of the indentation 34. In other words, each lug 48 protrudes from the bottom of the gallery in which the substantially cylindrical portion 18 of the rim 12 is adapted to lodge. With this arrangement, it will be appreciated that each of the recesses 20-23 effectively surrounds or encompasses one of the lugs 48. As seen in FIG. 1, each lug 48 consists of a first portion 50 protruding inwardly from the resilient annulus 28, a second portion 52 protruding at an angle toward the cavity 13 of the housing 10, a third portion 53 extending inwardly at right-angles to the second portion 52, and two spaced-apart ribs 54 extending upwardly from the edges of the third portion 53. Because the lugs 48 are integral with the resilient annulus 28, each lug 48 is itself resilient and is adapted to move between the position shown at the left in FIG. 3 and the position shown at the left in FIG. 4, in which latter position the lug 48 supports the reflective portion 46 of the sealed-beam lamp 14 in spaced relation with the lamp housing 10. In effect, the lugs 48 are squeezed or pinched between the reflective portion 46 and the interior of the lamp housing 10. Thus, the lip 42 of the resilient annulus 28 engages the sealed beam lamp 14 and urges it inwardly toward the cavity 13 and against the lugs 48.

As can be seen particularly in FIG. 2, the inner face of the lugs 48 is curved concentrically with the isolating ring 25.

The reason that the housing 10 and the isolating ring 25 of this assembly are provided with four recesses and four lugs, respectively, spaced at 90° intervals, is related to the desirability of being able to mount an auxiliary lamp on a truck in one of several orientations with respect to the horizontal. As is well known, each sealed-beam lamp is equipped with a lens having facets or reflective surfaces cut into it in a particular direction which makes the sealed-beam lamp suitable for a given orientation with respect to the horizontal. For example, usually the sealed-beam lamps are adapted to cast a beam of a certain cross-sectional shape, this cross section being often

elongated in one direction. In order to provide the lamp assembly of this invention with the necessary adaptability to permit a choice of mounting orientations, a four-lug design has been evolved which, firstly, permits the sealed-beam lamp to be oriented in a particular way with respect to the isolating ring 25, and which, secondly, permits the isolating ring along with the sealed-beam lamp to be oriented in one of four positions with respect to the housing, each of these directions being at right-angles to the adjacent two directions.

The way in which the sealed-beam lamp 14 is oriented with respect to the isolating ring 25 is clearly shown in FIG. 4. Most sealed-beam lamps are provided with an integral projection 60 just below the rim 45 on the reflective portion 46, the latter usually being made of glass. This projection 60 is generally rectangular in shape, and it is the intention of this invention to provide lugs 48 which are specifically adapted to enclose and "lockin'" the projection 60. This is the reason for the two ribs 54 which are clearly seen in FIG. 1. Thus, once the lamp assembly has been put together, there is no chance whatever that the sealed-beam lamp 14 can, through vibration, rotate with respect to the isolating ring 25, nor is there any possibility of the isolating ring 25 rotating with respect to the lamp housing 10, due to the interfitting of the lugs 48 with the recesses 20-23.

Thus, it is seen that the lamp assembly of this invention is capable of being mounted with its housing oriented in any of four mutually perpendicular directions, while still permitting the sealed-beam lamp to cast its beam in the desired orientation.

In FIG. 4, the housing 10 has a mounting hemisphere 62 securely fixed thereto, and a threaded shaft 63 projects from the hemisphere 62 in a direction substantially normal to the axis 32. The lamp assembly is mounted to the body of a vehicle by means of the shaft 63, the latter being adapted to swivel to a limited degree with respect to the housing 10, to permit adjustment of the lamp assembly. Thus, the lamp assembly of this invention can be mounted with the shaft 63 upright, horizontal leftward or horizontal rightward, for any of which the sealed-beam lamp 14 itself can be turned to a position in which the beam cast is in its intended orientation with respect to the horizontal.

While a particular embodiment of this invention has been shown and described herein, those skilled in the art will appreciate that changes and modifications may be made therein without departing from the spirit and scope of this invention as

defined in the appended claims.

I claim:

1. In combination,

a lamp,

a lamp housing having a circular rim, the rim defining the mouth of a cavity adapted to receive the lamp, the rim having four recesses spaced at 90° intervals, and an isolating ring consisting of a resilient annulus, an internal gallery in said annulus for receiving said circular rim, at least three lugs protruding inwardly from said annulus and adapted to register with said recesses when said circular rim is received within said gallery, a lip extending inwardly from said annulus for engagement with the lamp and for urging the lamp toward said cavity and against said lugs, thereby completely to isolate said lamp from direct contact with said lamp housing, said lamp having a projection adapted to register with one of the lugs, thereby to orient the lamp in one of at least three positions with respect to the isolating ring, each lug being shaped to receive said projection, whereby mutual rotation as between the lamp and the isolating ring is restrained.

2. The invention claimed in claim 1 or claim in which there are four lugs adapted to register with the four recesses.

3. The invention claimed in claim 1 or claim 1, in which said lugs protrude from said internal gallery.

4. The invention claimed in claim 1, in which said circular rim includes an annular flange portion extending substantially radially outwardly from the housing and a substantially cylindrical portion extending from the periphery of said annular flange portion in the direction away from said cavity, said recesses being defined by breaks in said substantially cylindrical portion, said substantially cylindrical portion being adapted to be received in said internal gallery.

5. The invention claimed in claim 1 or claim 1 in which the cross section of said resilient annulus taken in planes containing the axis of said resilient annulus is substantially constant, said cross section consisting of an elongated body portion of which the longer dimension is substantially parallel with said axis, the face of said elongated body portion which is adjacent said axis having a stepped indentation of which the deeper part provides the said gallery and of which the shallower part defines the inner wall of the said lip.
